UNITED STATES PATENT OFFICE.

GEORGE W. REAM, OF CANTON, OHIO, ASSIGNOR TO THE BUCHER & GIBBS PLOW COMPANY, OF SAME PLACE.

DESIGN FOR A STANDARD FOR PLOWS.

SPECIFICATION forming part of Design No. 32,130, dated January 23, 1900.

Application filed December 2, 1899. Serial No. 739,049. Term of patent 14 years.

To all whom it may concern:

Be it known that I, GEORGE W. REAM, a citizen of the United States, residing at Canton, in the county of Stark and State of Ohio, have 5 invented and produced a new and original Design for a Standard for Plows, of which the following is a specification.

In the accompanying drawings, Figure 1 is a front elevation of the standard. Fig. 2 is a 10 side elevation. Fig. 3 is a view of the opposite side. Fig. 4 is a plan view.

The leading feature of my design is in the shape of the standard both as to outline and surface configuration. The upper part of the 15 standard A inclines rearwardly and has a beveled front edge *a* and a rounded top and rear edge. Below the upper part A, which is approximately plain, two ledges *b* *c* occur, the

first, *b*, extending horizontally, while the second, *c*, is of right-angular formation bounding a recess *f*. A projection B extends rearwardly in an upward direction from about centrally of the standard. The wing C on the opposite side is shown in Fig. 1 and is curved and flaring. Fig. 4 is a plan view showing 25 the relative position of the parts and more particularly the form of the wing C. Fig. 3 shows the wing C and the opposite face of the part A, as at D.

I claim—

The design for a plow-standard as herein shown and described.

GEORGE W. REAM.
